UNITED STATES PATENT OFFICE.

ALFRED M. RODRIGUEZ, OF WESTFIELD, NEW JERSEY.

OIL BURNER.

Application filed August 20, 1925. Serial No. 51,435.

This invention relates to improvements in oil burners. An object of the invention is to provide a simple, efficient and compact burner construction whereby a minimum of oil is consumed to give the maximum of heating effect.

Another object resides in the provision of structural means whereby the oil, steam and air are most thoroughly mixed to produce the maximum combustion.

A further object concerns the provision of structural means whereby flames generated are most efficiently directed to cause the heating of water or other liquid in the burner.

15 A still further object concerns the provision of simple and efficient means whereby the oil is preheated.

The invention is illustrated in the drawings, of which—

20 Figure 1 is a side elevation partly in section of the device;

Fig. 2 is a section taken on the line 2—2 of Fig. 3;

Fig. 3 is a section on the line 3—3 of 25 Fig. 2;

Fig. 4 is a section on the line 4—4 of Fig. 2; and

Fig. 5 is an elevation of the perforated tube forming part of the oil preheating 30 means.

Fig. 6 is a section taken on the line 6—6 of Fig. 3.

The form of the invention shown in the drawings is a preferred form, although it is 35 understood that modifications in the construction and arrangement of the parts and in the character of the materials used may be adopted without departing from the spirit of the invention as set forth in the appended 40 claims.

In its general aspect the invention comprises a burner having a frame, a supporting ring mounted thereon above the frame, an adjustable air shutter between the supporting ring and the frame, an oil cup or bowl supported from the frame, an oil evaporating plate disposed within the bowl, an air deflector plate supported within the bowl above the evaporating plate, an air casing attached 50 to the bottom of the bowl, and a central oil column extending upwardly from the bottom of the bowl and through which the oil passes to be preheated, said central column acting as a conduit for additional air and 55 having at its top air and flame deflecting

means whereby the flame is guided and further mixed with air.

In the preferred form of the invention shown in the drawings, the burner is suitably supported within the furnace on a plate 60 10 having an opening 11 therein. Around the edge of this opening a ring 12 is disposed, and on this ring is mounted or fixed in any desired manner the base plate 13 of the burner. To the inner edge of this base 65 plate, which is generally ringlike in form, I mount a shell 14 having air apertures 15 therein. Around this shell I provide a slide- 70 able ring 16 having apertures 17 therein adapted to be aligned with the apertures 15 75 whereby air may pass from beneath the burner through these apertures to the furnace enclosure above the burner, without passing through the flame. This supplies an additional air regulating means. The ring 16 may be manipulated by means of a finger piece 18, shown in Fig. 2.

On the upper end of the shell 14 I mount a supporting ring 19. Screw bolts 20 connect the supporting ring 19 with the base 80 plate 13 and hold the shell 14 in place.

Suitably supported on the ring or plate 19 is an oil bowl 21 adjustably supported by means of bolts 22 at three points along its periphery with respect to the ring 19. This 85 oil bowl, on its bottom, is provided with an asbestos gasket 23 against which a water pan 24 is disposed. A pipe 25 feeds water to the pan 24. A hollow head 26 is suitably fastened to the bottom of the bowl 21. To 90 this head is threaded a hollow cylinder 27 extending upwardly from the center of the bowl. At its upper end this cylinder is provided with a metallic ring 28, partly closing the same. The bottom of the head 95 26 is disposed above the bottom of the bowl 21 by reason of legs 29 (see Fig. 4). The bottom of the head is closed by a ringlike plug 30. The inner edge of this plug is threadably engaged by an inner cylinder 31 100 provided with a plurality of perforations 32 throughout its periphery at definite levels. Screwed into the bottom of the bowl 21, and lying within the cylinder 31, is a tube 33 extending up through the ring or plug 28 105 and having a clamping ring 34 threadably engaged with its upper end and bearing against the upper surface of the plug 28. The plugs 28 and 34 as shown particularly 110 in Figure 6 are provided with inner longitu-

dinal grooves 34^a which permit the oil vapor which is generated within the column to escape and mix with the air deflected outwardly by the deflector plate 36. At the edge of plate 36 the mixture ignites. A deflector head 35 is mounted on the upper end of the cylinder 27, and suitably spaced above this deflector head 35 is a deflector plate 36 spaced from the head 35 by means of screws 37 and spacing sleeves 38. The upper end of the tube 33 opens beneath the plate 36. The lower end of the tube 33 opens below the bottom of the water pan 24. A clamping nut 39 holds the water pan 24 against the asbestos gasket 23. This nut engages the lower threaded end of the tube 33. The upper end of the cylinder 31 is open beneath the plug 28. A plurality of pipes 40 extend through the bottom of the bowl 21 and open into the chamber formed within the head 26 and between the cylinders 27 and 31. These pipes admit oil within these cylinders. The oil will rise within the head 26 until it reaches a level corresponding to the perforations 32 in the cylinder 31, where it will pass through, passing down within the cylinder 31 to the bottom of the bowl beneath the head 26. It will then spread out beneath an evaporating plate 41, which is shaped substantially conforming to the contour of the bottom of the bowl and spaced slightly thereabove. The ring on its inner periphery forms narrow oil passages 42 between its inner periphery and the head 26, and between its outer periphery and the bowl 21 oil passages 43 are formed. A pipe 41^a is disposed in the side of the bowl 21, just above the level of the top of the evaporating plate 41, so that if the oil rises to the level of the opening in this pipe it will overflow from the pipe and can be led to any desired location.

Along the lateral walls of the oil bowl, intermediate the bottom and the top thereof, are disposed a plurality of air openings such as 44 (see Figs. 1 and 2). These openings are of ample dimensions. Adjustably supported on screws 45 on a shoulder 46 within the oil bowl 21 is a deflector ring 47 which extends downwardly and outwardly within the bowl in front of the air opening 44 so that air passing therethrough will be drawn downward on to the top of the evaporating plate 41. The evaporating plate 41 is also adjustably supported on the bottom of the bowl 21 by means of adjustable screws 48 (see Fig. 4).

In the operation of the device the evaporating plate is adjusted at the proper height above the bottom of the bowl. The deflector plate 47 is likewise adjusted; the oil bowl itself is adjusted in the supporting ring 19, and the air openings 15 and 17 are properly registered either full or partly, as desired. Oil is then introduced into the pipes 40 and

will reach the level of the apertures 32, whence it will pass down along the inner surface of the tube 31 and flood the bottom of the bowl, rising through the openings 42 and 43, preferably the opening 43. The oil is then ignited, and as it heats the apparatus the oil flowing in through the pipes 40 will be vaporized between the cylinders 27 and 31. The vapor will rise between these cylinders, whereas the oil liquid will flow through the apertures 32. The oil vapor will rise to the top of the cylinder 31 and then pass down between it and the tube 33. Preferably this upper heating action on the oil will vaporize practically all of it, and most of the oil vapor will pass up between the inner periphery and the evaporator plate 41 and the edge of the head 26 through the passage 42. What oil is still liquid will flow out through the passage 43 on the top of the evaporator plate. The oil evaporated becoming ignited on top of the plate 41 will mix with the air which is drawn in through the openings 44 and deflected downwardly by the plate 47. This flame will pass upwardly and be deflected outwardly by the head 35. At this point, just beyond the top of the head 35, it will be mixed with a portion of air which rises through the top 33 and is deflected by the plate 36. If further air is needed within the furnace above the burner it can be admitted by adjusting the apertures 15 and 17 as above mentioned. This air will be drawn up from beneath the burner through the apertures into the furnace chamber around and above the burner. As the air passes up from beneath the burner, along the edge of the air openings 44, which by this time has become so heated that the water is boiling, it will draw some of the steam or water vapor with it and this steam will pass in with the air to mix with the oil vapor.

It is found that by providing a central oil preheating column, by providing an evaporator plate disposed in the manner described above the bottom of the oil bowl, and by admixing the air and steam with the oil in the manner above mentioned, a most efficient combustion is effected and a very hot flame is produced. This flame is properly directed by the construction of the apparatus to effect the utmost efficiency in the heating by whatever medium the system may employ, either air or water.

What I claim as my invention is:

1. An oil burner which comprises an oil cup, an oil evaporating plate disposed above the bottom of the cup, a central oil heating column having passages therein through which the oil passes to be preheated, said passages opening at the bottom of the column to permit oil to flow along the bottom of the cup, a central air passage in said column extending to the top thereof, an air

deflector plate at the top of the column, a flame deflector plate at the top of the column, the side of the cup provided with a plurality of air passages, and a deflector 5 ring supported within the cup to deflect the air downwardly onto the oil evaporating plate.

2. An oil burner which comprises an oil cup, a central oil heating column therein, 10 said column comprising a plurality of spaced cylinders forming oil passages, one of said cylinders disposed within another and provided with apertures intermediate its height to permit the oil introduced between the 15 cylinders to flow therethrough at predetermined levels.

3. In an oil burner, an oil cup, an oil evaporating plate disposed above the bottom of the cup, a central oil preheating column 20 comprising three cylinders concentrically disposed one within the other, means for introducing oil between the two outer cylinders, the inner cylinder of the said pair provided with a perforation intermediate its 25 height to permit oil to pass therethrough, a space between the inner cylinder and the intermediate one opening into the bottom of the cup, the space within the inner cylinder providing an air passage, a flame deflector at the top of the outer cylinder, and 30 an air deflector plate disposed on top of said flame detector.

4. In an oil burner, an oil cup, means centrally disposed with respect to and extending 35 upwardly from the bottom of the cup to form an oil preheating column, said column provided with an air passage, a flame deflector at the top of the column, and an air deflector at the top of the column, a 40 water pan disposed and supported against

the bottom of the cup, air openings in the side of the cup, a deflector ring disposed within the cup in front of the air opening to deflect the air downwardly on the oil evaporating plate, said air in its passage 45 by the water pan carrying water vapor and steam therewith into the cup.

5. An oil burner which comprises an oil cup, a central oil heating column therein, 50 said column comprising a plurality of spaced cylinders forming oil passages, one of said cylinders disposed within another and provided with apertures intermediate its height to permit the oil introduced between the cylinders to flow therethrough at a predetermined level, said cylinders at their upper ends having passages to permit the oil vapor to pass out at the top thereof.

6. In an oil burner, an oil cup, an oil evaporating plate disposed above the bottom of the cup, a central oil preheating column 60 comprising three cylinders concentrically disposed one within the other, means for introducing oil between the two outer cylinders, the inner cylinder of the said pair 65 provided with a perforation intermediate its height to permit oil to pass therethrough, a space between the inner cylinder and the intermediate one opening into the bottom of the cup, the space within the inner cylinder 70 providing an air passage, a flame deflector at the top of the outer cylinder, and an air deflector plate disposed on top of said flame detector, said cylinders at their upper ends having passages which permit the oil vapor to pass out beneath the deflector plate 75 so that the oil vapor will be deflected laterally with the cup.
